UNITED STATES PATENT OFFICE

JAMES C. MEEM, OF BROOKLYN, NEW YORK

TUNNEL STRUCTURE AND METHOD OF ERECTING SAME

Application filed August 12, 1932. Serial No. 628,486.

My invention relates to sub-aqueous tunnels, and has for its objects to provide a simplified and novel construction of tunnels and tunnel sections, and also new and improved methods of erecting and laying tunnels comprised in such sections. From certain aspects my present invention is an improvement on the invention disclosed in my pending application S. N. 469,386 filed July 21, 10 1930.

To the above and other ends which will subsequently appear my invention consists in features and methods of construction, combinations of devices and arrangements of 15 parts hereinafter described and particularly pointed out in the appended claims.

The type of sub-aqueous tunnel for which my present invention has been more especially designed is constituted by one or more tunnel sections which are erected in part on land and preferably completed above the surface of the water, and are subsequently submerged and positioned on a prepared sub-aqueous bed or foundation. Where the tunnel is constituted by a plurality of sections the sections are successively sunk to position and joined end to end. Each of the sections is comprised of a closed body or tunnel section proper and a buoyant shaft or shafts by which the sinking of the section to position is controlled. The tunnel element or section comprises end closures or diaphragms which have flat outer plane faces to enable them to be properly joined and connected to contiguous tunnel sections, and one of the specific objects of the present invention is to provide an improved and simplified end closure or diaphragm.

The buoyant shafts for controlling the sinking of the tunnel section by permitting the introduction of water or other means for overcoming its buoyancy have usually heretofore been connected at their lower ends with a chamber within the tunnel body, and in the invention disclosed in my aforesaid

application S. N. 469,386 the opposite ends or walls of this chamber have been constituted by the outer diaphragm and a wall or bulkhead spaced inward therefrom within the tunnel body and braced to the diaphragm. It is another object of the present invention to improve and simplify the construction of the aforesaid chamber, and generally stated this improvement resides in extending the buoyant shaft downward within the tunnel body and connecting it to the bottom thereof so that this extended or base portion of the buoyant shaft (or shafts) itself constitutes the water receiving or flooding chamber.

The invention will be more specifically described in connection with the accompanying drawings which illustrate a preferred form and wherein

Fig. 1 is a top plan view partly in section of a tunnel element or section embodying the invention in part;

Fig. 2 is an end elevation partly in section of the tunnel section;

Fig. 3 is a fragmentary vertical sectional view taken on a plane indicated by the section line 3—3 in Fig. 1 and looking in the direction of the arrows at said line;

Fig. 4 is a view corresponding to Fig. 3, showing two tunnel sections joined at their abutting end closures or diaphragms.

Fig. 5 is a fragmentary horizontal sectional view taken on a plane indicated by the section line 5—5 in Fig. 4; and

Figs. 6 and 7 are views corresponding respectively to Figs. 4 and 5 but showing the internal portions of the end closures or abutting diaphragms cut out, leaving only the permanent outer peripheral portions of the connecting diaphragms.

Each tunnel section as herein disclosed is generally rectangular in cross section, although it is to be understood that its shape may be varied within the scope of the invention. The section 10 comprises an exterior shell made up of metallic flanged plates 11

50

55

60

65

70

75

80

85

90

95

arranged longitudinally of the tunnel section. The plates on the bottom of the section have their flanges 12 upturned so that the bottom plates may lie flat against the ground or ways on which the section is erected, while the plates at the sides and top have their flanges turned outward so that they may be suitably joined together at their flanges from the outside. The bottom plates are similarly connected at their upturned flanges within the body. The framework of the tunnel within the shell is preferably of steel and concrete and is comprised of metallic beams 13 laid crosswise on the upturned flanges 12 of the shell bottom and which support vertical side columns 14 and intermediate columns 15, top cross-beams 16 being supported on the vertical columns, the described parts of the framework being suitably connected together.

In erecting the tunnel section, the shell plates 11 constituting the bottom are first laid down on an erecting floor or ways and connected together, and the sides of the shell for a few feet up from the bottom are also erected. Then preferably the inner framework 13-16 is built, the sides of the shell being thereafter completed and the shell being continued for a few feet inward on each side of the top, leaving the central portion of the top open, the shell being suitably secured to the framework within as by welded or bolted clips. Diaphragms or end closures previously built and next to be described in detail, are then raised, placed across the ends of the tunnel section and secured to the body in any suitable manner as by internal devices and also externally as by welding, riveting, bolting or the like.

The said internal devices or securing means preferably comprise adjustable tension or tie-back bolts or rods 7 spaced at intervals around the tunnel and extending through openings in angles or plate washers 8 which may be employed where required. As shown, angles 8 are attached to web plates embodied in the diaphragm, and corresponding plate washers not necessarily of angle form may be employed at the beams 13 and 16 where the tie-rods 7 project therethrough (see Figure 1). The outwardly projecting end portions of the tie rods are threaded to receive nuts 9 which when tightened suitably join and tie back the inner perimetric or permanent portion of the diaphragm to the body of the tunnel and also suitably tie together the interior structural framework. These series of tie-rods are preferably stepped alternately from side to side as shown in Fig. 1. If preferred, the tie rods 7 connecting the diaphragm with the structural framework of the tunnel body may be applied and adjusted after the abutting diaphragms of adjacent tunnel sections have been permanently connected together.

Each diaphragm or end closure indicated generally by the numeral 17 comprises a row or set of metallic channels or channeled members 18. These may be rolled unitary beams, or bars, or plates with attached flanges, the term beam being used generically herein. The flanges 19 of the channel beams 18 are inturned when the diaphragm is vertically in place, the channel beams then being vertically disposed. In erecting the diaphragm the channel beams or bars are laid with their flat faces downward against ways or a suitable plane-faced erecting floor. Between the channel beams are disposed web plates 20 having their outer edges flush with the smooth outer faces of the channels, the channels or beams and the web plates being secured together as by rivets passing through the flanges 19 and the intervening portions of the web plates. It is to these web plates 20 that the tie-rods 7 are attached. Secured to the inwardly extending portions of the web plates as by riveting are upright stiffening members, angles or angle bars 21. These angles 21 are parallel with the channel beams and are secured in pairs to the web plates in such relation that their inner oppositely extending angle portions provide flat faces which are in a substantially uniform plane parallel with the outer flat face of the diaphragm. The diaphragm is completed by providing horizontally disposed integral bracing and holding members 22 and 23 extending transversely near the top and bottom of the diaphragm and parallel with each other at its inner side. Said members may be of any suitable construction of the requisite strength and weight, as unitary or built-up metallic elements, reinforced-concrete elements, or the like. As herein shown by way of example these bracing and holding members are in the form of heavy I-beams or cross girders disposed with their flanges vertical and their webs horizontal, the inner flanges being secured by rivets 24 or other suitable means to the contiguous flanges of the angle bars 21 (Figs. 1 and 3). The top and bottom beams or members 22 and 23 perform the important function of bracing and maintaining the outer face of the diaphragm comprised by the smooth outer faces of the channel bars 18 to the true plane surface of their original buildings. It will be realized that by the present construction as heretofore generally outlined, the diaphragm is relieved of the varying pressure of the internal water column to which it was subjected when it constituted a wall of the water chamber, since by the present invention the water chamber (or chambers) is constituted by the base portions of the buoyant shafts, hereinafter more particularly described. The diaphragm is a unitary structure constituted by the parts described, and is erected in a flat substantially horizontal plane.

tal position and subsequently raised to a vertical or erect position and applied to the open end of the horizontally disposed tunnel section.

The top and sides of the outer face of the diaphragm are suitably extended outward as indicated at 18a to constitute a rim portion which provides a bolting area for the reception of bolts or rivets by which the diaphragm when sunk in place may be connected to the rim portion of the contiguous diaphragm of an adjacent tunnel section. It is preferable to dispense with the rim portion at the bottom of the outer diaphragm face in order to enable the diaphragm to be connected to the end of the tunnel section without interference on the erecting floor, and also to avoid the necessity of any especial preparation by trenching or the like in the bed of the tunnel, which is highly inconvenient, if not impracticable, and expensive.

As soon as the ends of the tunnel section 10 are sealed by the diaphragms 17 the section may be launched, a small amount of holding concrete having first been placed in the bottom if found desirable. The lower or base portions of the buoyant or buoying shafts next to be described are then placed in position and suitably attached to adjacent parts as by angles or plates welded or bolted in position.

Base portions each designated as a whole by the reference numeral 25 are provided for each buoyant shaft. Where the tunnel section is of considerable width as illustrated herein there may be two buoyant shafts near each end, arranged in pairs but separated, and if found desirable these shafts outside of the tunnel may be connected by tie-rods or suitable braces. The base portions or shaft bases 25 may be and preferably are constructed outside the tunnel section and erected or emplaced therein after it has been floated. Each shaft base as shown clearly in Figs. 1 and 2, is made up of structural metal comprising plates of channel bars 26 vertically disposed and suitably secured together as by welding by rivets 27 through their flanged portions. Where, as in the present instance, each side of the base 25 is constituted by a number of these elements or channel bars 26, it is desirable to provide interior cross ties or other bracing. As herein shown the cross ties are constituted by flat bars 28 secured at 29 to anchor plates 30 riveted between the flanges of associate channel bars 26 and projecting into the shaft base. The tie bars 28 are spaced at intervals lengthwise of the shaft base 25 and the sets of bracing bars preferably alternate at right angles to each other within the base, as shown. The upper end portion of the shaft base 25 may terminate in a seat

31 to which the lower portion of the associate buoyant shaft proper is secured.

The completed base portions or shaft bases 25 are placed in position in the tunnel section and suitably attached to adjacent portions of the tunnel body as by welded or bolted clips. To insure rigid connections of the base portions 25 with the body of the tunnel, a bottom concrete filling indicated at 33, and upper concrete filling indicated at 34 may be employed. The bottom filling 33 is solid, while the top filling 34 is formed with a suitable opening indicated at 35. It will be observed that when in position the shaft seat 31 of each base projects upward above the tunnel shell.

After the launching of the section, a concrete lining indicated at 36 is built, suitable forms being provided therefor. The laying of the shell plates of the roof is completed preferably while the tunnel is afloat and with some of the concrete lining in place.

Buoyant shafts indicated generally by the numeral 37 are attached to the shaft seats 31, preferably prior to launching. These buoyant shafts are extensions of the bases or shaft chambers 25 to which they are connected through the openings 35, and may be of substantially the construction of the base portions 25. Each buoyant shaft may if necessary be composed of a number of sections applied successively one on top of another and suitably connected together.

When completed and launched, the tunnel section, virtually awash, is floated to position over the prepared bed or foundation. A piping and valve system not shown herein of suitable construction for controlling the flow of water to the base portions 25 may be employed, and as a result the tunnel section may be sunk under control to position on its bearing bed, after which divers may pull the section into contact with one previously emplaced, the abutting diaphragms 17 being brought into close contact and permanently connected as by bolts 32 through the flanged peripheral portions or bolting areas 18a. Any spaces or openings between the outer rim portions are sealed by packing, calking or in any other suitable manner, as indicated at 18b. Thereafter the buoyant shafts are unbolted and the openings 35 sealed as by concrete and overlying metallic covers, and the valves and any valve openings are closed. Later the tunnel is entered and the inner portions of the contacting diaphragms are cut out, after connecting by riveting or bolting the permanent peripheral rim portions 18c (Figs. 6 and 7) which may be further secured as by interior bolting. Any openings around the inner edges of these portions where the diaphragms join are calked or otherwise permanently sealed, as indicated at 18d.

The outstanding rim portions 18a afford 130

adequate means for connecting the abutting diaphragms of tunnel sections along the sides and top. At the bottom where there are no outwardly extending rim portions I prefer to employ a gasket 38 or a facing of viscous material, such as tar, which may be applied along the bottom outer face of the diaphragm and also if desired at other portions of its contacting face before submerging, such coating or gasket being for the purpose of insuring a water-tight connection between abutting diaphragms. The lateral re-inforcing means constituted by the lower bracing beam 23 is relatively quite heavy and functions to hold the bottom portion of the diaphragm in close substantial contact with that of the contacting diaphragm to which it is bolted at the top and sides, as well as co-operating with the upper bracing beam 22 to hold the outer or contact face of the diaphragm in a flat condition or plane when it is lifted from the erecting floor and attached to the end of the associate tunnel section.

It will be observed that the base portions 25 constitute internal shafts or flooding or loading chambers which provide means for sinking the tunnel to its bed, and which, in association with connected external chambers or aligned shafts for buoyancy control, regulate such sinking or submersion. Or, the buoyant shafts may be regarded as extending down independently into the body of the tunnel section, and bottoming on the bottom of the section. Further, it will be noted that 35 these internal shafts or flooding chambers are independent of each other as well as of the body of the tunnel, and that as a result of employing small separate flooding chambers the sinking is better controlled both 40 lengthwise and widthwise and the expense reduced owing to the simplification of the flooding chambers as compared with prior constructions.

I claim:

1. A tunnel section having an end closure comprised of flanged channel members having their flanges inturned to present a smooth outer surface, and cross beams spaced apart 50 and arranged transversely of the channel members to hold the smooth outer surface in a true plane; and means for permanently connecting the end closure to the body of the section.

2. A tunnel section having an end closure comprised of flanged channel members having their flanges inturned to present a smooth outer surface, and cross beams spaced apart and arranged transversely of the channel 60 members to hold the smooth outer face in a true plane; and means for permanently connecting the end closure to the body of the section comprising a series of adjustable tie bolts spaced at intervals around the tunnel section 65 and each having one end connected to the end

closure and the other end to the structural framework of the tunnel section.

3. A tunnel section having an end closure comprised of flanged members having their flanges inturned to present a smooth outer surface, and cross beams spaced apart and arranged transversely of the channel members to hold the smooth outer face in a true plane; and means for permanently connecting the end closure to the body of the section, 70 said means comprising a series of adjustable tie-bolts spaced at intervals around the tunnel section and each having one end connected to the end closure and the other end to the structural framework of the tunnel section, 75 the peripheral portion of the end closure and the body portion of the section being also additionally secured together.

4. A tunnel section provided with an end closure composed of flanged channel beams, 80 the flanges being inturned to provide a smooth outer surface for the closure, inwardly extending web plates fixed between the channel beams, angles secured to the inner end portions of the web plates in parallelism with the channel beams, and bracing beams disposed transversely of the angles and secured thereto; and means for attaching the end closure to the body of the tunnel section.

5. A tunnel section provided with an end closure comprised of upright channel bars with inturned flanges, upright web plates disposed between and secured to the flanges of the channels, upright angles secured to the inner end portions of the web plates and having oppositely disposed portions in a general uniform vertical plane parallel with the outer face of the closure, and a pair of transverse beams arranged across the angles near the top and bottom of the closure, the webs of the beams being horizontal and their flanges vertical and the flanges of the beams contiguous to the angles being secured to their said oppositely disposed portions; and means for attaching the end closure to the body of the tunnel section.

6. A tunnel section provided with an end closure comprised of upright channel beams with inturned flanges, upright web plates disposed between the flanges of the channel bars and riveted thereto; upright angles secured to the inner end portions of the web plates and having oppositely disposed portions in a general uniform plane, and a pair of transverse I-beams arranged across the angles near the top and bottom of the closure, the webs of the beams being horizontal and their flanges vertical and the flanges of the beams contiguous to the angles being secured to their oppositely disposed portions; and means for attaching the end closure to the body of the tunnel section comprising a series of adjustable tie bolts spaced at intervals around the tunnel section and each having one end connected to the end closure and the opposite 120 125 130

end to the structural framework of the tunnel section.

7. A tunnel section provided with an end closure comprised of upright channel beams with inturned flanges, upright web plates disposed between the flanges of the channel bars and riveted thereto; upright angles secured to the inner end portions of the web plates and having oppositely disposed portions in

10 a general uniform plane, and a pair of transverse I-beams arranged across the angles near the top and bottom of the closure, the webs of the beams being horizontal and their flanges vertical and the flanges of the beams

15 contiguous to the angles being secured to their oppositely disposed portions; and means for attaching the end closure to the body of the tunnel section comprising a series of adjustable tie bolts spaced at intervals around the

20 tunnel section and each having one end connected to the end closure and the opposite end to the structural framework of the tunnel section, and sealing the outer meeting portions of the closure and the contiguous closure 25 to which it is joined.

8. A tunnel section provided with an end closure composed of flanged channels, the flanges being inturned to provide a smooth outer surface for the closure, inwardly extending web plates secured between the channels, angles secured to the inner end portions of the web plates in parallelism with the channels, and bracing beams disposed transversely of the angles and secured thereto, and means for attaching the end closure to the body of the tunnel section, the peripheral portion of the closure extending outward beyond the sides and top of the shell of the tunnel section to provide areas for bolt holes,

35 and the outer plane face of the closure being provided with one or more gaskets or viscous coatings.

9. A tunnel section having an end closure comprised of flanged channels having their flanges inturned to present a smooth outer face, and cross beams spaced apart from each other and from the channels and arranged transversely of the channels to hold the smooth outer face in a true plane; and means

45 for permanently connecting the end closure to the body of the section, the peripheral portion of the closure extending outward beyond the sides and top of the shell of the tunnel section to provide areas for bolt holes, and the outer plane face of the closure being provided with one or more gaskets or viscous coatings.

10. A tunnel section comprising diaphragms for closing its ends and joining it to the diaphragms of adjacent tunnel sections, said diaphragms having their peripheries extended at the top and sides outward beyond the body of the section to provide bolting areas and having a relatively heavy

50 cross beam arranged crosswise of it inside and near the bottom to hold the bottom in substantial contact with the contiguous diaphragm of an adjacent tunnel section when their contacting diaphragms are bolted at the top and sides.

11. A tunnel section comprising a body and end diaphragms having their peripheries extended at the top and sides outward beyond the body of the section to provide bolting areas and having a relatively heavy cross member arranged crosswise of it inside and near the bottom to hold the bottom in substantial contact with the contiguous diaphragm of an adjacent tunnel section when their contacting diaphragms are bolted at the top and sides, a coating of viscous material such as tar being provided across the outer faces of each diaphragm prior to joining its tunnel section with the diaphragm of an adjacent tunnel section.

12. A sub-aqueous tunnel section comprising a body having closed ends, a shaft independent of said ends and extending downward into the body and bottoming on the bottom of the body, said shaft being open

55 at the top and serving as a flooding chamber to assist in sinking the tunnel section to a submerged bed, and an external buoyant shaft connecting with the opening at the top of said independent shaft.

13. A sub-aqueous tunnel section comprising a body having closed ends, an internal loading chamber of structural metal erected independently of the body and emplaced

60 therein and secured thereto, said chamber having an inlet at the top of the body, and an external buoying structural metal chamber connecting to the inlet of the internal chamber.

14. A sub-aqueous tunnel section comprising a body having ends closed by unitary diaphragms, a loading chamber of structural metal erected independently of the body and subsequently mounted therein, said chamber

65 having an inlet at the top of the body, and an external shaft connecting with said opening.

15. A sub-aqueous tunnel section comprising a body having closed ends, independent internal shafts arranged one near each end of the body and extending downward therein, said shafts having closed bottoms and terminating at their tops in shaft seats external of the tunnel body, and external

70 buoyant shafts secured to said shaft seats and opening into said internal shafts.

16. A sub-aqueous tunnel section comprising a body of rectangular cross section and provided with end diaphragms and internal shafts arranged in pairs, one pair near each end of the tunnel body inside the diaphragms, said shafts having closed bottoms and open

75 tops at the top of the body, and external buoyant shafts extending upward from the body in alignment with said internal shafts

70

and opening into said internal shafts, and extending above the top of the water when the section is sunk to its foundation.

17. A sub-aqueous tunnel section comprising a body having closed ends, and shafts secured to the body and having internal portions bottoming on the bottom of the body and external portions extending upward outside the body, the shafts throughout their lengths being of substantially uniform construction and comprising intermediate seats fixed to the top of the body.

18. A method of building diaphragms for and attaching them to the ends of a tunnel section which comprises laying parallel rows of channels on a flat substantially horizontal surface with their flanges upturned, attaching thereto upright web plates, attaching angles to the upper portions of said plates parallel with said channels, attaching cross beams to the angles to hold the face of each diaphragm in a flat plane when it is lifted, raising the completed diaphragms to vertical positions and attaching them to opposite ends of the tunnel section by internal devices, and also sealing them to the ends of the tunnel sections, the top and sides only of each diaphragm projecting outward beyond the rim of the tunnel section to provide bolting areas.

19. A method of building diaphragms for and attaching them to the ends of a tunnel section which comprises laying parallel rows of channels on a flat substantially horizontal surface with their flanges upturned, attaching thereto upright web plates, attaching angles to the upper portions of said plates parallel with said channels, attaching cross beams to the angles to hold the face of each diaphragm in a flat plane when it is lifted, raising the completed diaphragms to vertical positions and attaching them to opposite ends of the tunnel section by internal devices, and also sealing them to the ends of the tunnel sections, the top and sides only of each diaphragm projecting outward beyond the rim of the tunnel section to provide bolting areas, and then coating portions of the outer face of each diaphragm with a viscous substance such as tar, and finally attaching a flat gasket to an outside portion of the bottom area of each diaphragm.

20. A method of building diaphragms for and attaching them to the ends of a tunnel section which comprises laying parallel rows of channels on a flat substantially horizontal surface with their flanges upturned, attaching thereto upright web plates, attaching angles to the upper portions of said plates parallel with said channels, attaching cross beams to the angles to hold the face of each diaphragm in a flat plane when it is lifted, raising the completed diaphragms to vertical positions and attaching them to opposite ends of the tunnel section by internal devices,

and also sealing them to the ends of the tunnel sections, the top and sides only of each diaphragm projecting outward beyond the rim of the tunnel section to provide bolting areas, erecting shafts of structural metal independent of the tunnel body, the lower portions of said shafts extending downward within the tunnel body and suitably attached thereto, the bottoms of said shafts being closed, the upper portions of said shafts extending upward from outside of the top of the tunnel body to above the water level for buoyancy control, the lower portions of said shafts providing loading chambers.
